UNITED STATES PATENT OFFICE.

DENNIS C. O'SHEA, OF CHICAGO, ILLINOIS.

KNITTED GARMENT.

1,356,168.

Specification of Letters Patent. Patented Oct. 19, 1920.

Application filed May 29, 1917. Serial No. 171,662.

To all whom it may concern:

Be it known that I, DENNIS C. O'SHEA, a citizen of the United States, residing at Chicago, in the county of Cook and State 5 of Illinois, have invented a new and useful improvement in Knitted Garments, of which the following is a specification.

My invention relates to certain new and useful improvements in knitted garments, 10 and is especially applicable to garments of the type of sweater jackets, which are formed of a plurality of sections of relatively heavy knitted fabric secured to one another by seams. It is an object of my invention to provide means by which the 15 seams of such a garment may be adequately reinforced without sacrificing the inherent advantages of knitted garments.

It is a further object of the invention to 20 improve the fit of the garment, particularly as to the collar and shoulders thereof. It is a still further object to provide reinforcing means of such a character that the half mittens formed on the sleeve ends in 25 accordance with the invention of my application for golfer's jacket filed May 29, 1917, Serial No. 171,661, may be advantageously employed.

My invention will be fully understood 30 from the following detailed description of a specific embodiment thereof, taken in connection with the accompanying drawings, in which—

Figure 1 is an inside face view of a 35 knitted sweater jacket spread open to expose the seams thereof, and Fig. 2 is an enlarged view of the left-hand portion of the collar and shoulder seams, showing the means employed to reinforce the same.

It will be understood that it has heretofore been the practice to reinforce the seams of knitted garments, such as sweater jackets, by the use of a strip of woven fabric of sufficient strength to meet the strains 45 imposed in the use of the garment. This practice answered the immediate purpose of reinforcing the seam, but entailed the disadvantage of sacrificing the perfect elasticity of the garment. The method of reinforcement heretofore employed has also 50 failed to overcome the tendency common to knitted garments of the nature of jackets to gape or pull away at the neck and shoulder. By my invention this defect is removed.

According to my invention, the collar seam, designated in the drawing by the numeral 10, and the shoulder seam, designated 11, by which the sleeves are joined to the collar and shoulders are reinforced by 60 strips of knitted fabric designated 12 and 13, respectively, these knitted strips being preferably formed of the same yarn which is employed in the body of the garment, being the same color, and identical in all 65 respects with the material of the garment itself, save that in their knitting a stitch is employed which is closer and stronger than the stitch employed in the garment. These reinforcing strips 12 and 13 are secured to the inner face of the garment and overlap the meeting edges of the seamed parts, the arrangement being shown in the drawings.

The same method of reinforcement may 75 be employed for securing the buttons along the front of the jacket, as indicated at 14 in Fig. 1, and at any other place.

By my invention all of the inherent advantages of a knit garment are fully retained in spite of the fact that the garment is made up of a plurality of sections joined by seams. These seams are adequately reinforced by reinforcing strips of knitted fabric, as described, but the seams when reinforced still retain the same elasticity and ability to yield in every direction to conform to the curves and to the movements of the body, which is possessed by the garment itself.

Among the other advantages of my present invention may be mentioned the following: The reinforced seams being capable of stretching in every direction in the same manner as the garment itself, there is no 95 danger of the garment becoming deformed and ill-fitting through unequal stretching of the adjacent parts, as is the case where the seams are rigidly held in their original form by an inelastic reinforcing strip; 100 wrinkling or deformation of the garment through unequal shrinking is likewise obviated; and the appearance of the garment is much improved.

Since the reinforcing strip 12 runs in a 105 straight line around the collar portion of the garment, extending along this collar seam a considerable distance beyond the shoulder joint, the collar portion is rendered stiffer and the tendency to fall away from the 110

shoulder or neck exhibited by knitted garments in particular is overcome, the collar being caused to hug closely to the neck. The 5 separate reinforcing strips 13 which are used for the sleeve seams adequately strengthen these parts without permitting the natural pull upon the sleeve to cause the garment to gape at the neck.

The arrangement of the knitted fabric reinforcing strips shown and described is of 10 peculiar benefit in connection with a garment having mitten backs formed integrally on the ends of the sleeve as shown at 14', and designed to be caught over the 15 knuckles of the wearer, as by finger loops 15, this construction being fully described in my co-pending application referred to. Where such mitten backs are secured to the 20 sleeve ends, the natural tendency of a close-fitting sleeve to pull away from the shoulder may be aggravated, particularly if the sleeves are not of sufficient length.

By the use of the knitted fabric reinforcements 13 on the shoulder seams connected by the intermediate portion of the 25 knitted reinforcement 12 on the collar seam, the entire garment from one sleeve end across the shoulder and collar and down to the other sleeve end is elastic and free to yield. 30 By adding the elasticity of the shoulder or collar portion to that of the sleeves all danger of ripping or tearing at the shoulder seam is obviated, and, furthermore, the outward pull upon the sleeve sections is not 35 transmitted to the collar in such a manner as to cause the same to gape.

While I have shown and described in 40 considerable detail one specific embodiment of my invention, it will be understood this is illustrative only and for the purpose of making the invention more clear and that I do not regard the invention as limited to

these details nor to any of them, except in so far as such limitations are included within the terms of the accompanying claims in 45 which it is my intention to claim all novelty inherent in my invention as broadly as is permissible in view of the prior art.

What I claim as new, and desire to secure by Letters Patent, is:

1. A knitted jacket comprising a knit body portion, collar and sleeves, the said parts being joined by seams, a reinforcing strip of knitted fabric more closely knitted than that of the body extending along the 55 inside face of the collar seam from a point in front of the shoulder on one side to a corresponding point on the other side, and separate reinforcing means of the same character as said first-named reinforcing 60 strip applied to the inner faces of the sleeves and joining them with the said collar reinforcement.

2. A knitted jacket comprising a knit body portion, collar and sleeves, the said 65 parts being joined by seams, extensions carried by the said sleeves, means for securing said extensions to the hand of the wearer, and knitted fabric seam reinforcing means joining the said sleeves to the said collar.

3. A knitted jacket comprising a knit body portion, collar and sleeves, the said parts being joined by seams, a reinforcing strip of knitted fabric lying over the inside 75 face of the collar seam and extending from a point beyond the shoulder on one side to a point beyond the shoulder on the other side, separate knitted fabric reinforcements connecting the said reinforcing strip with the said sleeves, extensions carried by said sleeves, and means for securing said extensions to the hands of the wearer.

DENNIS C. O'SHEA.
